Attorney

UNITED STATES PATENT OFFICE.

HANS GAFNER, OF ESCANABA, MICHIGAN.

ADJUSTABLE SHOE LAST.

Application filed April 12, 1922. Serial No. 551,964.

To all whom it may concern:

Be it known that I, HANS GAFNER, a citizen of the United States, residing at Escanaba, in the county of Delta and State of Michigan, have invented a new and useful Adjustable Shoe Last, of which the following is a specification.

The object of my invention is to provide an improved shoe repair outfit having a plurality of means for adjusting it and comprising the novel combination and arrangement of parts illustrated in the accompanying drawings. I attain these and other objects of my invention by the mechanism shown in the drawings, in which—

Figure 1 is a side elevation of the invention;

Fig. 2 is a rear end or edge elevational view looking in the direction of arrow A;

Fig. 3 is a horizontal section on line 3—3 of Fig. 1;

Fig. 4 is a detail vertical sectional view on line 4—4 of Fig. 1;

Fig. 5 is a detail view of member 22; and

Fig. 6 is a horizontal section on line 6—6 of Fig. 1.

Like numerals indicate like parts in each of the several views.

Referring to the accompanying drawings, I provide an adjustable shoe last consisting of two like front form members 1 and 2 and a single rear or heel form member 3. Integral with the shank of form members 1 and 2 I provide similar form members 1^a and 2^a extending at right angles to form members 1 and 2. The foot form of members 1^a and 2^a are of a different size from the foot form of members 1 and 2, one of these forms being for ladies' shoes and the other being a larger size for men's shoes. The heel form members 3 and 3^a are proportioned accordingly for women's and for men's shoes, respectively. Heel form member 3 is provided with a rack portion 6 which is vertically adjustable on a corresponding rack portion 7 of the upright lower extension member 5. Rack portions 6 and 7 are adjustably secured in the desired engaged position by a suitable bolt and thumb screw 8, as shown in Fig. 1. I provide an adjustable base extension 4 having spaced slots 11 of suitable size to receive the bolt 9 which extends through a bifurcated end of the upright extension piece 5 and which functions as a pivot and support.

For the purpose of providing longitudinal adjustment of the shoe last I provide a rear adjusting screw 12 mounted in the rear form member 3 and having a large washer or head 13 as shown in Fig. 6, disposed to bear on both members 1 and 2. This member functions to adjust the distance of heel form member 3 from the main foot form members 1 and 2. In order to provide lateral adjustment of the foot form members 1 and 2, I provide a lateral screw 14 mounted in member 1 having a suitable blunt head or washer bearing against the other foot form member 2. I provide a similar lateral adjusting member 15 for the base foot form members 1^a and 2^a. Members 1^a and 2^a are provided with suitable hollowed-out portions 16 for the purpose of lightening the weight of these members. I provide flanges 19 connecting the shanks of members 1 and 1^a and 2 and 2^a, respectively, as shown in Figs. 1 and 3, and extending through these flanges 19 I provide a bolt 17 and springs 18 interposed between the ends of the bolt and outer surfaces of the respective flanges 19. I provide suitable base supporting flanges 20, as shown in Fig. 3. I provide suitable apertures 21 in front form members 1 and 1^a, to receive the spindle of a suitable small semi-spherical member 22, as shown in Fig. 5, which is removably attachable, as shown.

The rear heel member may be lifted from one position on extension 4 to a different position, its bolt 9 engaging in one of the slots 11. The upper portion of the heel may be adjusted to extend or shorten the last by adjusting the screw 12. The front foot form members 1 and 2 are adjusted laterally by the lateral adjusting screw 14, members 1^a and 2^a are adjustably spaced apart and laterally adjustable by means of the adjusting screw 15. Rear foot form member 3 and its extension 5, together with the slotted bar 4 may be reversed to the dotted line position shown in Fig. 1 so that the heel form will cooperate with form members 1^a and 2^a, adjusting screw 12 bearing against said members for longitudinal adjustment, as before. The form members 1^a and 2^a are for men's shoes and have the larger foot form designated 24, as contrasted with the smaller foot form 23 for ladies' shoes in which members 1 and 2 terminate. The operation of the said members is similar as above described and as shown in the drawings.

What I claim is

1. In an adjustable shoe last the combination of like foot form members, a second set of like foot form members, the first foot form members and the second foot form members having integral shanks, means resiliently securing the shanks of said members in spaced relation, means for adjustably spacing the first foot form members from each other, means for adjustably spacing the second foot form members from each other, a single heel form member, means for supporting said heel form member in position to cooperate with either set of foot form members, and means, for adjusting the heel form member relative to either set of foot form members.
2. In an adjustable shoe last, the combination of like foot form members divided longitudinally of the foot, means for adjustably spacing said members in a direct lateral direction from each other, a second similar set

of foot form members of different size from the first set, means for adjustably spacing said second form members in a direct lateral direction from each other, a notched bar mounted on the shank of said members, a heel form member adjustably and removably mounted on the slotted bar, means for spacing said heel form member for either of the previously named foot form members, means for attaching the mechanism to a suitable support, resilient means engaging the shanks of said foot form members to resiliently hold same in a desired spaced relation, and means for adjustably securing the heel form member in a desired elevated or lowered position relative to the first foot form members or in an extended or retracted position relative to the second foot form members according to which members it is aligned to cooperate with, substantially as shown.

HANS GAFNER.
